UNITED STATES PATENT OFFICE.

LEVI DAVIS, OF ALTON, ILLINOIS, ASSIGNOR OF ONE-HALF TO JOSEPH F. PORTER, OF SAME PLACE.

MEANS FOR THROWING RAILWAY-SWITCHES.

SPECIFICATION forming part of Letters Patent No. 674,626, dated May 21, 1901.

Application filed October 27, 1900. Serial No. 34,550. (No model.)

To all whom it may concern:

Be it known that I, LEVI DAVIS, a citizen of the United States, residing at Alton, in the county of Madison and State of Illinois, 5 have invented certain new and useful Improvements in Means for Throwing Railway-Switches, of which the following is a full, clear, and exact description, reference being had to the accompanying drawings, forming part of 10 this specification.

My invention relates to a means whereby the movable switch-points of street-railway tracks may be operated by the motorman or other person while upon the car.

15 My invention consists in features of novelty hereinafter fully described, and pointed out in the claims.

Figure I is a top view of the throwing device with parts shown in horizontal section. 20 Fig. II is a view, partly in vertical section, on line II II, Fig. I, and partly in side elevation. Fig. III is an enlarged detail sectional view taken on line III III, Fig. I. Fig. IV is an enlarged detail perspective view of one of the 25 switch-throwing devices. Fig. V is a detail view of the rear end of the swinging frame that carries the switch-throwing tongue, the view being taken in the direction indicated by the arrow, Fig. IV. Fig. VI is an enlarged 30 detail view illustrating the switch-throwing tongue and the parts by which it is carried, the frog being shown in cross-section. Fig. VII is a top view of the parts seen in Fig. VI. Fig. VIII is an enlarged detail view of the 35 central portion of the rocking bar through which the switch-throwing tongue is manipulated. Fig. IX is a plan view of a section of railway track and frog of the construction used with my switch-throwing means. Fig. 40 X is an enlarged perspective view of the rail-frog. Fig. XI is a cross-sectional view taken on line XI XI, Fig. X.

1 designates the platform of a car beneath which my switch-throwing means is suspended.

2 designates hangers in which the ends of a rocking beam 3 are journaled.

4 designates frames, each having arms 5 and 6. The frames 4 are pivoted to the rocking beam 3 by bolts or pins 7 and are permitted 50 to swing sidewise to a limited extent, but

when at rest are held approximately at right angles to the beam 3 by springs 8, (see Fig. V,) the springs having two arms that straddle fingers 9, fixed to the frames 4. Whenever 55 the frames 4 are swung sidewise in the manner and for the purpose hereinafter to be stated, the fingers 9 press against one of the arms of the springs 8, and as soon as the frame is released from sidewise pressure the springs, 60 by pressing against the fingers 9, return the frames 4 to normal position. The frames 4 and the parts carried thereby are of similar construction, and the more complete description of such parts hereinafter given will be 65 understood to apply equally to both. One is designed to throw switch-points at one side of the track and the other for switch-points at the other side of the track.

10 designates a vertical shaft journaled in 70 the outer ends of the arms 5 and 6 of each frame 4, and rigidly carried by the shaft 10 at its lower end is the switch-throwing tongue 11, that is adapted to partake of the movement imparted to said shaft, as will herein- 75 after appear. The shaft 10 is normally held in such a position that the tongue 11 is projected approximately in alinement with the lower arm 6 of the frame 4, the shaft being so held through the medium of a finger 12, 80 applied to the shaft at its upper end and straddled by a two-arm spring 13, that is secured to the frame 4. The spring 13 permits a limited rocking movement of the shaft 10 and tongue 11; but bearing against the finger 85 12 always returns the parts to their normal positions when at rest.

The rocking beam 3 is connected to the car-platform by springs 14, that normally maintain the frames 4 and parts carried thereby 90 elevated from the ground, as seen in Fig. II.

15 designates a swivel mounted in a bearing-bracket 16, carried by the rocking beam 3. This swivel is provided with a pair of apertured arms 17 and a finger 18.

19 designates connecting-rods seated at one end in the arms 17 of the swivel 15 and connected at their opposite ends to bell-crank 20, pivotally connected to hangers 21, suspended from the car-platform. The free ends of these 100 bell-crank receive the bearing of the inner ends of push-pins 22, (see Fig. II,) loosely

seated in the car-platform, where they are in convenient position for the motorman or other operator's foot, by which, upon the depression of the push-pins, the bell-cranks 20 5 are rocked to effect strain upon either of the connecting-rods 19 at will for the purpose of rocking the beam 3 and swiveling the swivel 15.

23 designates a rocking bar centrally pivoted at 24 to the rocking beam 3, (see Figs. II, III, and VIII.) The two arms of said rocking bar extend outwardly from the pivot 24 and are provided at their outer ends with forks 25. The rocking bar 23 is also provided 15 with a central fork 26, located directly above the pivot 24, and which receives the finger 18, carried by the swivel 15.

27 designates a rocking lever centrally pivoted at 28 to the frame 4 and having an arm 20 29, loosely arranged in the fork 25 of the rocking bar 23. The opposite end 30 of the rocking lever 27 is loosely seated in one arm of a two-arm cam 31, that is pivotally mounted in a slot contained by the shaft 10.

32 designates a rail-frog, and 33 a switch-point pivoted to the frog in the usual manner. The rail 34 of the frog is provided with a notch 35, and the guard-rail 36 is provided with a notch 37, coincident with the notch 35. Located outside of the rail 34 and guard-rail 36 are guide-rails 38, each provided with a bulge 39.

In practical use the parts are operated as follows: When the car to be switched approaches the switch-point 33, the operator places his foot upon one of the push-pins 22, according to the position of the switch-point 33 to be thrown. The downward movement of the push-pin rocks the coincident bell-crank 20, and thereby effects a strain upon the connecting-rod 19, attached thereto. The movement of the connecting-rod is imparted to the swivel 15 through the connection to the arm 17 thereof. The swivel 15 is therefore moved in its bearing, and at the same time the rocking beam 3 is rocked in its bearings and carries the frames 4 therewith to carry the switch-throwing tongue 11 to the frog 32. In such movement of the parts the throwing-tongue 11, that is to move the switch-point to be operated, descends into a position between the rail 34 and guard-rail 36 of the frog 32. At the same time that the parts named are actuated as described the turning of the swivel 15 causes the finger 18, carried by said swivel, to impinge against the fork 26 and rock the rocking bar 23 to move the inner end 29 of the rocking lever 27 upwardly. This movement of the lever 27 causes the outer end 30 60 of said lever to be thrown downwardly and carry the cam 31 therewith. Then as the car proceeds the depressed end of the cam 31, having been lowered into alinement with the guide-rails 38, strikes the adjacent guide-rail 38 and moves in contact with the bulge 39 thereof. The result is that the contacting

end of the cam 31 is thrown rearwardly and the shaft 10, on which the cam is mounted, is rocked in its bearings, causing the switch-throwing tongue to be thrown to one side into the notch 35 or 37 to enter behind the free end of the switch-point 33 in the manner illustrated in Fig. VII. The throwing-tongue 11 thus passes to one side of the switch-point, and as it continues its travel through the frog it throws the switch-point to the opposite side of the channel between the rails 34 and 36, where it is in position to receive the car-wheels and cause the car to be switched as desired. When the switch-point has been thrown, the operator releases the push-pin 22, and the parts are all returned to their normal positions by the springs applied to them, as described.

I claim as my invention—

1. In a switch-throwing means, the combination of a switch-point-engaging tongue, a laterally-swinging frame in which said tongue is rockingly mounted, and means for rocking the tongue independently of the movement of said frame to cause it to engage the switch-point, substantially as described.

2. In a switch-throwing means, the combination of a switch-point-engaging tongue, a laterally-swinging frame whereby said tongue is carried, a rocking beam by which said frame is supported, means for rocking said beam, and means for rocking said tongue independently of the movement of said beam and frame, substantially as described.

3. In a switch-throwing means, the combination of a rocking shaft, means whereby said shaft is carried, a switch-point-engaging tongue carried by said shaft, and a cam carried by said shaft adapted to engage a projection protruding from the railway-track to rock said shaft and tongue, substantially as described.

4. In a switch-throwing means, the combination of a rocking shaft, means whereby said shaft is supported, a switch-point-engaging tongue carried by said shaft, a cam carried by said shaft, said cam being adapted to engage a projection protruding from the railway-track, and means for moving said cam to said projection, substantially as described.

5. In a switch-throwing means, the combination of a rocking shaft, means whereby said shaft is supported, a switch-point-engaging tongue carried by said shaft, a cam mounted in said shaft adapted to engage the rail-frog, a rocking lever connected to said cam, and means for rocking said lever to throw said cam into engagement with said projection, substantially as described.

6. In a switch-throwing means, the combination of a rocking beam, means for rocking said beam, a frame supported by said beam, a rocking shaft mounted in said frame, a switch-point-engaging tongue carried by said rocking shaft, a spring arranged to yieldingly hold said shaft, a cam mounted in said shaft,

and means for rocking said cam to throw it into engagement with the rail-frog, substantially as described.

7. In a switch-throwing means, the combination of a rocking beam, a frame carried by said beam, a rockingly-supported switch-engaging tongue, a rocking shaft by which said tongue is carried, a cam mounted in said shaft, a rocking lever connected to said cam, a rocking bar having engagement with said lever, and means for rocking said bar to move said lever and cam, substantially as and for the purpose set forth.

8. In a switch-throwing means, the combination of a rocking beam, a frame carried thereby, a switch-engaging tongue, a rocking shaft by which said tongue is carried, a cam mounted in said shaft, a lever having connection with said cam, a rocking bar having connection with said lever, a swivel carried by said rocking beam, and provided with means for engaging said rocking bar, and

means for rocking said beam and swivel, substantially as described.

9. In a switch-throwing means the combination of a switch-point-engaging tongue, means whereby said tongue is rockingly carried, means for rocking said tongue to cause it to engage the switch-point, and a spring arranged to return said tongue to normal position after it has been rocked, substantially as described.

10. In a switch-throwing means, the combination of a switch-point-engaging tongue, a laterally-swinging frame in which said tongue is rockingly mounted, means for rocking said tongue to cause it to engage the switch-point, and a spring arranged to return said frame to normal position after it has been swung laterally, substantially as described.

LEVI DAVIS.
